United States Patent Office.

ARCHIBALD TROLAN, OF NORWICH, CONNECTICUT.

Letters Patent No. 91,055, dated June 8, 1869.

IMPROVEMENT IN MACHINE FOR DOUBLE-SEAMING SHEET-METAL.

The Schedule referred to in these Letters Patent and making part of the same.

To all whom it may concern:

Be it known that I, ARCHIBALD TROLAN, of Norwich, in the county of New London, and State of Connecticut, have invented a new and improved Machine for Folding or Double-Seaming Sheet-Metal Roofing; and I do hereby declare that the following is a full, clear, and exact description of the construction and operation of the same, reference being had to the annexed drawings, making a part of this specification, in which—

Figure 1 is a vertical sectional view of the machine cut through the centre.

Figure 2 is a vertical sectional view of one end, in which the folding-plate is drawn down in contact with the tin to be folded.

Figure 3 is a transverse section of the end, cut across the centre, as per line x, fig. 2, in which the lock-ring that projects into the folding-bar is shown.

Figure 4 is a sectional view of a part of the centre of the machine, showing the clamp-screw that holds the removable plate by which the height of the machine is governed to fit the work.

Figure 5 is an end view of the tin, after the first folding-movement.

Figure 6 is an end view of the tin, after the first fold is pressed down.

Figure 7 is an end view of the tin, after the second fold is turned and pressed down.

The object of the invention is to provide for public use a machine for folding or double-seaming tin or sheet-metal roofing, and press the seams down tightly in a much more perfect and expeditious manner than has ever been done before.

In the drawings, A indicates the frame of the machine.

B, the handle by which it is lifted from place to place.

C, the folding-bar, to which is attached the handle D, by which bar C is turned over to fold the tin.

E is a lever-handle, pivoted on pin e, for the purpose of closing the clamp-folding plate F against the tin g, as shown in fig. 2, for the purpose of folding, as shown in fig. 5.

G is a spring that throws handle E down, and opens the folding-clamp F, when relieved by the hand, after folding the tin, as shown by fig. 5.

H is a projecting part on the frame A, turned out true with the hole h, and projects into either end of the folding-bar C, thereby forming a guide that holds the folding-bar C up snug in the bearings of hole h.

I is the false bed, held to the machine by thumb-screw J, and used only when the first fold of the tin is made, to raise the machine the proper height from the roof to close on the tin in the proper place, as shown by fig. 2, when the folding-clamp F is closed on to the tin, ready for folding, as shown by fig. 5.

When the second fold is made, the clamp is removed, which lets the machine down on the roof the

thickness of the first fold, and in the right place for the second fold, or to clamp the tin, as shown at fig. 6, and folding, as shown at fig. 7.

The operation is as follows:

The tin is first placed upon the roof in the ordinary way, with the edges turned up at right angles with the roof, and one about one-fourth of an inch above the other, as shown in fig. 2.

The operator then takes the machine, (with the false bed I attached, as shown by fig. 1,) by handle B, places it over the upturned edges of the tin g, and with the other hand the operator closes the handle E up to handle D, and thereby closing the folding-plate F against the highest of the upturned edges of the tin, and tightly clamps it against the folding-bar C, as shown in fig. 2.

The handles D and E are then raised up while tightly closed together, which revolves the folding-bar and folds the tin over the point of folding-plate F, as shown in fig. 5.

The operator then lets the handles spring apart, while in nearly a perpendicular position, and the folding-plate F drops down, so as to clear fold g, fig. 5, when the handles or folder is let back to the position, fig. 1, this operation being repeated the entire length of the seam, when the operator raises the machine, closing the handles D and E, thereby closing the folding-plate F close up to the folder C.

He then places the machine on the seam, and the handles are thrown over while being pressed tightly together, bringing the outside of the folding-plate F against the angling edge of the tin g, fig. 5, and pinches it against the front rail of the frame at K, closing the seam down tightly, as shown in fig. 6, and repeating the same movement the length of the seam.

The bed I is then removed, which lets the machine down on the seam, and in the proper position to turn a double seam, which is done by repeating the movements above described, which completes the work and leaves the seam as shown in fig. 7.

Claims.

What I claim, and desire to secure by Letters Patent, is—

1. The clamping-plate F, when used in combination with the folder C and frame A, substantially as and for the purpose specified.
2. The projecting guide-part H, of frame A, when used as a guide for folder C and clamping-plate F, substantially as described.
3. The removable plate I, when used in combination with frame A, folder C, and clamping-plate F, for the purpose specified.

A. TROLAN.
